DESIGN FOR A WALL POCKET

Freda Diamond, New York, N. Y., assignor to Syracuse Ornamental Co. Inc., Syracuse, N. Y., a corporation of New York

Application April 5, 1946, Serial No. 128,325

Term of patent 14 years

(Cl. D33—18)

To all whom it may concern:

Be it known that I, Freda Diamond, a citizen of the United States, residing at New York, in the county of New York and State of New York, have invented a new, original, and ornamental Design for a Wall Pocket, of which the following is a specification, reference being had to the accompanying drawing, forming a part thereof.

Fig. 1 is a front perspective view of a wall pocket showing my new design; and

Fig. 2 is a partial front perspective view thereof in inverted position.

I claim:

The ornamental design for a wall pocket, substantially as shown.

FREDA DIAMOND.
